UNITED STATES PATENT OFFICE.

GEORGE O. HOPPE, OF CHARLOTTE, ILLINOIS.

SPOT OR HILL MARKER FOR SEED-PLANTING MACHINES.

1,279,546.

Specification of Letters Patent. Patented Sept. 24, 1918.

Application filed February 26, 1918. Serial No. 219,199.

To all whom it may concern:

Be it known that I, GEORGE O. HOPPE, a citizen of the United States, and a resident of the village of Charlotte, county of Livingston and State of Illinois, have invented 5 certain new and useful Improvements in Spot or Hill Markers for Seed-Planting Machines, of which the following is a specification.

10 My invention relates to improvements in seed planting machines, and more particularly to the spot or hill marker used in connection therewith, the present application being a division of my pending application 15 Serial #167,824, filed May 10, 1917, for Seed Planting Machines.

The object of my invention is the production of a marking device of the character mentioned, which will be of durable and 20 economical construction and highly efficient in use. Other objects will appear hereinafter.

The invention consists in the combinations and arrangements of parts hereinafter described and claimed.

25 The invention will be best understood by reference to the accompanying drawings forming a part of this specification, and in which;

30 Figure 1 is a top plan view of the rearward end portion of a seed planting machine equipped with a marking device, embodying the invention, the ground-engaging element being shown in section,

35 Fig. 2, a rear elevation of the ground-engaging element and the adjacent portion of the arm carrying the same, and

Fig. 3, an enlarged detail section taken substantially on line 3-3 Fig. 2.

40 The preferred form of construction, as illustrated in the drawings, comprises an elongated arm 4 swingingly connected at 4' with the rearward end of the frame 5 in connection with which the device is employed.

45 The arrangement is such that the arm 4 may be swung to extend from either side of the machine in order to effect marking of the ground at either side thereof, as will be readily understood by those skilled in the art.

50 The outer end of the arm 4 is enlarged and flattened, and formed therein is an arcuate slot 7 in which is arranged a vertically disposed ground-engaging member or marker 8. Said member 8 is formed midway its ends 55 with a flange or lip 9, which is pivotally connected at 10 with the portion 6 of arm 4, said

portion 6 being provided with a rearwardly opening slot 11 to accomodate said lip 9. The arrangement is such, as will be seen, that the member 8 is adapted for oscillatory movement about the axis 10, that is about a vertical axis, when the arm 4 is in horizontal or operative position.

Marker 8 is normally held in central position, that is, in a position in which the enlarged or widened ends thereof are positioned parallel with the direction of movement of the machine, by means of helical compression springs 12 which engage against opposite sides of said arm, being interposed 60 between said sides and the corresponding ends of slot 7.

Oscillation of the marker 8 about the axis 10 is effected by means of a cord 13 which is connected with the rearward end of the lip 9. The cord 13 passes along the arm 4 through guide loops or eyes 14, the same thence passing forwardly to the front end of the machine where the same is operatively connected with tripping mechanism associated with the seed dropping mechanism of the planter, as will be readily understood by those skilled in the art. A turn buckle 15 is interposed in the cord 13 to afford adjustment, and a weight 16 is provided at the 70 outer end of the arm 4 to insure the sinking of the end of the marker into the ground, in the operation of the planter.

The arrangement is such as will be seen, that as the machine travels along the ground, 75 the lower end of the marker 8 will pierce the ground and form a straight line parallel with the direction of movement of the machine. As the seed dropping mechanism is 80 operated, the cord 13 will be simultaneously jerked or pulled with the result that the marker 8 will be given a sudden rocking or oscillatory movement about the vertical axis 10 causing the formation of a sort of jog or break in the line made by the marker, the 85 jogs thus made marking the spots or hills identifying the position of the deposit of seeds. The arm 4, being swingingly mounted may, as above pointed out, be positioned to extend from either side of the machine, 90 and the marker 8 being double ended, the marking device will be as effectual at either side of the machine, which is of course essential in order to coöperate with the machine in traveling in one direction and then 95 in the other.

While I have illustrated and described the

preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:—

1. In a seed planter, a marking device comprising an arm carried by the planter; a ground-marking element mounted on said arm for oscillatory movement about a vertical axis; means for oscillating said ground-marking element about said axis, and means for yieldingly holding said ground-marking element in central position, substantially as described.

2. In a seed planter, a marking device comprising an arm carried by the planter; a ground-marking element mounted on said arm for oscillating movement about a vertical axis; means for oscillating said ground-marking element about said axis; and resilient means engaging against opposite sides of said ground-marking element for holding the same in central position, substantially as described.

3. In a seed planter, a marking device, comprising an arm carried by the planter; an elongated vertically disposed ground-marking element; a rearwardly projecting lip on said ground-marking element connected with said arm so as to permit of oscillatory movement of said element about a

vertical axis; and means engaging with said lip for oscillating said ground-marking element, substantially as described.

4. In a seed planter, a marking device, comprising an arm carried by the planter; an elongated vertically disposed ground-marking element; a rearwardly projecting lip on said ground-marking element connected with said arm to permit of oscillatory movement of said element about a vertical axis; means engaging with said lip for oscillating said ground-marking element; and resilient means engaging against opposite sides of said ground-marking element for holding the same in central position, substantially as described.

5. In a seed planter, a marking device comprising an arm carried by the planter; a ground-marking element mounted on said arm for oscillating movement about a vertical axis; means for oscillating said ground-marking element about said axis; and resilient means engaging against opposite sides of said ground-marking element for holding the same in central position, said arm being slotted to afford clearance for said ground-marking element in the oscillatory movement thereof, and to accommodate said resilient means, substantially as described.

In testimony whereof I have signed my name to this specification in the presence of two subscribing witnesses.

GEORGE O. HOPPE.
